TRANSDUCER TUBE

J. Kenneth Trolan, McMinnville, Oreg., assignor to Research Corporation, New York, N. Y., a corporation of New York

Application February 2, 1954, Serial No. 407,701

4 Claims. (Cl. 313—148)

The invention relates to devices which convert a mechanical motion into an electrical response and particularly to transducers employing an electronic vacuum tube with a field emission cathode.

The purposes of the invention are to provide a means of altering the surface electric field at the cathode of a field emission tube, by the motion of one or more electrodes, thus producing simultaneously a change in the field dependent emission current; to provide a transducer utilizing the characteristics of the field emission cathode to obtain high sensitivity of current response to electrode motion, miniaturization and high frequency response, negligible power required by the cathode and dissipated elsewhere, and wide range of current and voltage over which the device is useful.

Numerous types of transducers are known in the art. Most transducers are of either the magnetic or piezo-electric type although thermionic tubes with movable control grids are used in certain specialized applications.

The thermionic transducers with movable control grids are difficult to manufacture and are also quite fragile and susceptible to damage by mechanical shock. They lack the sensitivity of the devices of present invention and require appreciable heat energy, and its dissipation, with correspondingly increased weight and size. The latter also limits the frequency response of the device. Piezo-electric and magnetic transducers are essentially low power and low voltage devices and cannot be used in high voltage or high power applications without bulky and expensive amplifying systems. Magnetic transducers employing an electrical conductor moving in a magnetic field will convert mechanical motion into electrical response, but the electrical output is independent of the position of the conductor when it is at rest. For this reason magnetic transducers are not as versatile or sensitive as is desired in order to control and/or measure the motion and position of some mechanical device.

One of the characteristics of field emission is the exponential dependence of field current density J on the cathode electric field F , which dependence is given approximately by the equation:

$$J = Ae - \frac{b}{F} \quad (1)$$

where J is in amperes/cm.², F is the electric field at the cathode surface in volts/cm. and A and b are constants which depend on the type of cathode material used. It is known that the electric field at the surface of a field emitter is dependent on both the electrode geometries and their mutual spacings and applied potentials ("The Field Emitter: Fabrication, Electron Microscopy, and Electric Field Calculations," Journal of Applied Physics, vol. 24, No. 5, 570-576, May 1953), and that a small change in the spatial relationship of the electrodes, at constant voltage, can cause a large change in the emitted field current density from the cathode ("Field Emission: Large Current Densities, Space Charge, and the Vacuum Arc," Physical Review, vol. 89, 799-808, February 1953).

2

The primary purpose of this invention is to utilize the characteristics of the field emitter in a vacuum tube in which the electric field at the cathode surface and hence its field emission current density can be varied by the movement of one or more of the electrodes in the tube. Because of the exponential dependence of J on F (Eq. 1), there results from the present invention a highly sensitive transducer of mechanical motion to electrical response.

The invention will be more fully described with reference to the accompanying drawing in which—

Fig. 1 is a section elevation of a transducer tube embodying the principles of the invention;

Fig. 2 is a fragmentary enlarged view of the electrode elements of the tube;

Fig. 3 is a fragmentary enlarged view of the electrode arrangement of another embodiment of the invention; and

Fig. 4 is a fragmentary enlarged view of the electrode arrangement of a further modification of the invention.

Equation 1 requires an electric field of 10^7 to 10^8 volts/cm. at the cathode surface for appreciable field emission; this can be accomplished at reasonable electrode potentials by providing a cathode surface with a small radius of curvature, for example, shaped as a cone with a hemispherical tip of radius 10^{-5} to 10^{-3} cm. In Fig. 1 is shown a discharge vessel 1 which contains such a field emission cathode 2 mounted on a support filament structure 3. Field emission of electrons from the cathode 2 occurs when the field control electrode 4 has a suitable position and positive potential relative to the cathode, the electrons then proceeding through the relatively transparent electron suppressor 5 and being collected at the plate electrode 6. Motion of the field electrode 4 relative to the cathode 2 causes a change in the cathode field in spite of a constant potential difference between those electrodes and that change causes an appreciably greater change in the amplitude in the current at the plate 6, in view of Eq. 1. The device shown in Fig. 1 therefore provides a highly sensitive transducer of mechanical motion between electrodes 2 and 4 into electrical response at electrode 6. Relative motion of the cathode 2 with respect to the tube electrode 4 may be effected by either or both of two means, (a) motion of the cathode 2 which is permitted by compression of the expansion bellows 9 through externally applied forces and (b) motion of the electrode 4 through a force applied on its lever arm 7 which is permitted by the flexible inseal 8.

Figure 1 shows the details of tube construction. An electric current may be passed through the wire filament 3 to heat the filament by the resistive generation of heat. The cathode 2 will then be heated by conduction from the filament and can thus be outgassed, cleaned and smoothed. The anode 6 is an electron collector and should be at a higher electrical potential than 2. The grid 5 is a secondary electron suppressor and should be at or near the potential of the cathode. The electrode 4 is movable and its position relative to the cathode 2 controls the electric field at the cathode surface, for a given value of the applied potential. In this tube both the cathode and electrode 4 are movable although satisfactory operation with simplified construction may be obtained by having only one movable electrode.

Fig. 2 is an enlarged detail of the electrode arrangement shown in Fig. 1. The movable control electrode 4 is shown as a wire loop or ring, but may take other forms. Position 4a represents the probable mean position of the control electrode 4 when it is desired to hold it at high potential relative to the cathode. The electric field at the cathode surface will then increase as the control electrode 4 is moved towards the cathode causing a large change in the emission current from the cathode. The emission current will be contained in a cone with a vertex

angle of about 100°, the axis of the cone being parallel to the emitter axis so the electrons will pass through the center of the control electrode 4 and be collected on the anode 6. In this case the operation of the transducer is relatively independent of the potential of anode 6 which can be adjusted to meet other circuitry requirements as long as it is at least a few volts positive with respect to the cathode. The secondary electron suppressor grid 5 should be at or near cathode potential.

Position 4b of the control electrode 4 is suitable if it is desired to maintain the control electrode 4 at a potential near that of the cathode (positive or negative). In this case for a suitable choice of potential on electrode 4, the emission current will decrease as the control electrode 4 is moved toward the emitter tip and will increase as it is moved away from the emitter tip. In this case the electric field at the cathode tip is influenced by the charge on both of the electrodes 5 and 6; this necessitates that they be at a sufficiently high potential with respect to the cathode to obtain the desired field current. Electrodes 5 and 6 may be tied together electrically or electrode 5 may be made slightly less positive than electrode 6 to minimize electron collection on electrode 5.

There are several methods for transmitting mechanical motion through vacuum seals. The flexible bellows 9 (Fig. 1) is designed to form a vacuum tight junction. It can be made of glass but such a bellows is very fragile so that some material such as Kovar that can be sealed to the glass envelope 10 is preferable. The flexible diaphragm 8 may also be made of Kovar or other material that can be sealed into the glass envelope. For most applications the tube envelope 10 may be made of metal or some ceramic material. This provides a more rugged design and simplifies the sealing on of flexible diaphragms or adjustable bellows.

Fig. 3 illustrates a multi-electrode transducer in which the controlling electrode 13 is separate from the field emission cathode 12, and the electron collecting anode 11. In this case the electric field at the cathode surface is varied by altering the spacing between 12 and 13. If the control electrode 13 is near cathode potential, electron emission from the cathode will decrease as the electrode 13 is moved towards the cathode 2; if, however, 13 is considerably more positive than 12, electron emission will increase as the spacing between 12 and 13 is decreased. The potentials of the three electrodes can be altered independently to obtain desired operating conditions. A secondary electron suppressor grid similar to electrode 5 in Fig. 1 may be included in a practical tube design in order to minimize secondary electron effects in cases where the electrode 13 is more positive than electrode 11. In Fig. 3, the control electrode 13 is shown as a hemispherically capped cylinder, but there are many geometries that would serve the purpose, such as a ring, helix or cylinder around the emitter, or a disc with a hole through which the emitter could protrude.

Fig. 4 shows a two electrode transducer with an anode 14 which is maintained at a positive potential relative to the field cathode 15. The potential necessary to cause usable field emission from the cathode is dependent on both the cathode-anode spacing and on the physical dimensions of both electrodes (primarily of the cathode); however, by a suitable choice of electrode geometries, the tube can be designed for operation at a desired voltage level. For a given potential, the magnitude of the electric field at the cathode surface is dependent on the cathode-anode spacing so that any variation in this spacing causes a large change in the emission from the cathode in view of Eq. 1. Fig. 4 indicates motion of the cathode 15 from position 15a to 15b; however, that movement is mentioned only as an illustration since the same desired effect could be obtained by moving the anode or by moving the cathode and anode simultaneously.

The field emission cathode may be of any useful geometry or material. Single needle-shaped emitters whose

tips have radii of curvature of 10^{-3} to 10^{-5} cm. have proven satisfactory in operation as have numerous needle-shaped emitters operating in parallel. Other geometries with small radii of curvature such as razor edges, have given substantial field emission. It is well known that the effective work function of metals can be altered by coating the surfaces with suitable materials. For example, coatings of barium, cesium or thorium lower the effective work function of tungsten while oxygen or hydrogen increase its work function. In some cases it may be desirable to coat the cathode surface with suitable materials to alter the work function or to increase the stability of electron emission or both.

The transducer of the invention has several advantages due to the characteristics of the field emission cathode. The primary advantage is the extreme sensitivity of the emission current to changes in electric field. For example, the emission current from a cathode whose work function is 4.5 electron volts, will increase by a factor of 100 if the electric field at the cathode surface is increased from 3.0×10^7 volts/cm. to 3.8×10^7 volts/cm. The transducer of the invention is also extremely versatile in that it can be used over a wide range of voltage and current. This is a distinct advantage over piezoelectric or magnetic transducers as these devices are limited to lower power and low voltage application. A further advantage is the micro-geometry of the cathode which facilitates miniaturization of the tube and makes possible tube designs in which a very small amount of mass needs to be moved. This increases both the sensitivity of the device and frequency at which it may be operated.

The motion of the transducer electrodes can be controlled by means other than the direct transmittal of mechanical motion from sources external to the device. Simplified construction can be obtained for many applications by using a magnetic field to move the electrodes. Ferromagnetic material can be included in an electrode which could then be moved by forces exerted by a magnetic field. The electrode can be mounted so that a displacement of the electrode is necessary to balance the force caused by the magnetic field, for example by spring mounting an electrode so that the force exerted by the spring is directly proportional to the displacement. If the force exerted by the spring is equal and opposite to the force caused by the magnetic field, the displacement of the control electrode will be directly proportional to the magnetic field strength. Such a device can be used to measure magnetic fields or as a magnetic amplifier.

The movement of the electrodes can also be controlled by the thermal expansion of a metal support or a bimetallic strip. For example, the movable electrode can be mounted on or connected to a bimetallic strip of wire that can be heated directly by the passage of electric current or indirectly by having a small heating element adjacent to it. The movement caused by this thermal expansion controls the field emission current so that low voltage used for heating can be made to control a high voltage circuit. Infra-red radiation can be used to control the temperature of the tube elements and the device can thus be used as an infra-red detector.

Obviously, there are many similar uses for tubes embodying the principles of the invention.

I claim:

1. A transducer tube for converting mechanical movement into electrical variations comprising an evacuated envelope, an electrode assembly in said envelope including a field emission cathode having an electron emitting portion of radius of curvature not exceeding about 10^{-3} centimeters, a collector electrode spaced therefrom and at least one auxiliary electrode positioned adjacent the electron emitting portion of said cathode and transparent to the flow of electrons between said cathode and collector electrode, and means for effecting relative motion of an electrode of said assembly to alter the field strength at said electron emitting portion of said cathode.

2. A transducer tube as defined in claim 1 including means for moving said cathode with respect to said collector electrode.

3. A transducer tube as defined in claim 1 including means for moving said auxiliary electrode with respect to said cathode.

4. A transducer tube as defined in claim 1 wherein said envelope includes a flexible member in the wall thereof and a member passing from the exterior of the

envelope to the interior thereof supported by said flexible member and interiorly connected to an electrode of said electrode assembly.
